UNITED STATES PATENT OFFICE.

WILLIAM F. DUNCKER, OF STEELTON, PENNSYLVANIA, ASSIGNOR TO JACOB SHAAR, OF SAME PLACE.

CAR-FENDER.

SPECIFICATION forming part of Letters Patent No. 529,370, dated November 20, 1894.

Application filed March 6, 1894, Serial No. 502,563. (No model.)

To all whom it may concern:

Be it known that I, WILLIAM F. DUNCKER, a citizen of the United States, residing at Steelton, in the county of Dauphin and State 5 of Pennsylvania, have invented a new and useful Car-Fender, of which the following is a specification.

The invention relates to improvements in car fenders.

10 The object of the present invention is to simplify, improve and increase the efficiency of fenders for electric, cable and other motor cars, to cause the brake to be automatically applied simultaneously with the bringing of 15 the fender in operative position, and to provide the fender with a track brake.

The invention consists in the construction and novel combination and arrangement of parts, hereinafter fully described, illustrated 20 in the accompanying drawings and pointed out in the claims hereto appended.

In the drawings—Figure 1 is a perspective view of a car provided with a fender constructed in accordance with this invention 25 shown in its lowered or operative position. Fig. 2 is a similar view, the fender being raised. Fig. 3 is a longitudinal sectional view.

Like numerals of reference indicate corresponding parts in all the figures of the drawings.

30 I designate a curved fender of any desired construction hingedly suspended from the front of a car 2, and adapted to be swung downward to bring it in operative position, and designed, when not in use, to be elevated, 35 as illustrated in Fig. 2 of the accompanying drawings, in order to be clear of the track.

The fender, which is preferably composed 40 of transverse slats 3 and curved end-bars 4 of angle iron, is pivotally connected at the upper ends of the bars 4 at 5 with the car. It is provided with rearwardly extending connecting bars 6 having their front ends 7 pivotally attached to the end bars 4 of the fender, and having their rear ends bifurcated to 45 form openings or slots 8, which loosely engage a transverse brake beam 9. The brake beam is suspended in the usual manner, and carries the usual brake-shoes 10; and when the fender is lowered to bring it into operative po-

sition the connecting bars are carried rearwardly, moving with them the brake-beam, thereby forcing the brake-shoes into engagement with the wheels and automatically applying the brake. The connecting bars serve 55 to brace the fender, when the latter is in operative position, and by having their rear ends loosely connected with the brake-beam, the fender is adapted to rise to give to any inequality of the track, or to pass over an 60 obstruction without liability of straining or otherwise injuring the connection between it and the brake-beam.

The fender is provided at its bottom, adjacent to its ends, with brake-shoes 11 arranged 65 to engage the track, or the rails thereof, to form a track brake to assist in retarding the forward motion of the car to effect a rapid stopping of the same. The brake-shoes 11 are attached to the end bars 4, and the connecting bars 6 are parallel, and are arranged 70 at opposite sides of the car adjacent to the brake-shoes of the fender and the brake-beam, which is the most advantageous position for bracing and supporting the parts, and their 75 beveled front ends rigidly engage the fender when lowered.

The fender is swung downward into operative position by a vertically disposed ratchet bar 12 operating through a slot 13 of the bottom of the car, and provided at its top with a foot plate 14 to be engaged by the foot of the motorman, and having its lower end connected by a spiral spring 15 with an arm 16 of the fender. The ratchet bar is provided 85 with teeth at its rear edge arranged to engage a stationary stop plate 17 for holding the fender depressed. The arm 16 extends forward and downward from the top of the fender; and the spiral spring forms a yielding connection or cushion between the arm and the ratchet bar to permit the fender to yield readily to any inequality of the track, without injury, which might result were the parts 90 rigidly mounted.

95 The fender is normally held elevated by springs 18 mounted on the car and engaging the fender or connected therewith.

In winter the fender may be provided with an oppositely curved flange 19, which will en- 100

able the fender to serve as a snow-plow or track cleaner; and any construction of flange may be employed for this purpose.

It will be seen that the fender is simple and 5 comparatively inexpensive in construction, that it may be readily applied to any ordinary construction of car, and that it is capable of being readily thrown into operative position, and of effecting a simultaneous application 10 of the brake of the car together with an application of its track brake.

Changes in the form, proportion and the minor details of construction may be resorted to without departing from the principle or 15 sacrificing any of the advantages of this invention.

What I claim is—

1. The combination with a car having a transverse brake beam carrying brake-shoes, 20 of a fender hingedly connected with and suspended from the car and located in advance of the brake-beam, and a bar extending from the fender to the brake beam, and having its front end movably connected with the former 25 and loosely connected at its rear end to the brake-beam, substantially as and for the purpose described.
2. The combination with a car having a transverse brake-beam carrying brake-shoes, 30 of a fender hingedly connected with and suspended from the car, and located in advance of the brake-beam, and a connecting bar having its front end pivotally attached to the fender and provided at its rear end with an 35 opening loosely receiving the brake-beam, substantially as described.
3. The combination with a car, of a fender

hingedly connected therewith, a vertically movable ratchet bar mounted on the car means for engaging the ratchet bar and locking the 40 same against upward movement, and a spring forming a yielding connection between the ratchet bar and the fender to permit the latter to yield to any inequalities of a track or the like, substantially as described. 45

4. The combination with a car, of a fender suspended therefrom and hingedly connected therewith, and provided with a forwardly extending arm, a ratchet bar mounted on the car means for engaging the ratchet bar to lock 50 the same against upward movement, and provided at its upper end with a foot plate, and a spiral spring interposed between the lower end of the ratchet bar and said arm and forming a yielding connection, substantially as 55 and for the purpose described.

5. The combination with a car having a transverse brake-beam carrying brake-shoes, of a fender hingedly connected with the car and located in advance of the brake-beam, 60 connecting bars having their front ends pivotally attached to the fender and having their rear ends loosely connected with the brake-beam, brake-shoes arranged at the bottom of the fender, and a yielding connection between 65 the fender and the car for holding the former depressed, substantially as described.

In testimony that I claim the foregoing as my own I have hereto affixed my signature in the presence of two witnesses.

WM. F. DUNCKER.
